UNITED STATES PATENT OFFICE

NATHAN OTTINGER, OF NEW YORK, N. Y.

DESIGN FOR A FOLDER OR SIMILAR CONTAINER CONSTRUCTED OF FLEXIBLE MATERIAL

Application filed April 22, 1931. Serial No. 39,595. Term of patent 14 years.

To all whom it may concern:

Be it known that I, NATHAN OTTINGER, a citizen of the United States, residing at New York, in the county of New York and State of New York, have invented a new, original, and ornamental Design for a Folder or Similar Container Constructed of Flexible Material, of which the following is a specification, reference being had to the accompanying drawings forming part thereof.

Figure 1 is a front elevation of a folder or similar container, showing the same closed;

Fig. 2 is a similar view, showing the container open;

Fig. 3 is a longitudinal edge view as seen from the top in Fig. 1, and

Fig. 4 is a similar view of the right hand end of the closed container shown in Fig. 1.

I claim:

The ornamental design for a folder or similar container, constructed of flexible material, as herein shown.

NATHAN OTTINGER.
